UNITED STATES PATENT OFFICE.

JAMES M. HOLLAND, OF MOUNT PLEASANT, IOWA, ASSIGNOR TO THE MOUNT PLEASANT ROAD GRADER COMPANY, OF SAME PLACE.

ROAD-SCRAPER.

SPECIFICATION forming part of Letters Patent No. 484,429, dated October 18, 1892.

Application filed March 14, 1892. Serial No. 424,881. (No model.)

To all whom it may concern:

Be it known that I, JAMES M. HOLLAND, a citizen of the United States, residing at Mount Pleasant, in the county of Henry and State of Iowa, have invented a new and useful Road-Scraper, of which the following is a specification.

This invention relates to improvements in road-scrappers, the objects and advantages of the same being hereinafter described, and more particularly pointed out in the claims.

Referring to the drawings, Figure 1 is a side elevation of a road-scraper constructed in accordance with my invention. Fig. 2 is a plan. Fig. 3 is a longitudinal section. Fig. 4 is a detail in perspective of the scraper-blade. Fig. 5 is a detail in perspective of the locking-latch for the blade. Fig. 6 is a detail in perspective of the adjustable connection between the crank-arms and the supporting-rods of the blade. Fig. 7 is a detail in perspective of one of the scraping-wings.

Like numerals of reference indicate like parts in all the figures of the drawings.

In practicing my invention and in constructing the framework for the scraper I employ opposite pairs of longitudinally-disposed and parallel side beams 1, preferably of angle-iron, mounting the front ends of the same upon the bolster 2 and the rear ends upon pairs of standards 3. The rear standards 3 are supported upon the rear axle 4, and between the inner standards of the opposite pairs there is located a platform 5. The bolster 2 rests upon the front axle 6, and a king-bolt 7 passes through the bolster and axle, as is usual. The axles are provided with ground-wheels 8, and the front axle with suitable draft devices 9. Mounted loosely upon the king-bolt 7 is a draft-bail 10 and loosely engaging the bail and adapted for vertical and lateral movement thereon is the usual scraper-bar 11. A horizontally-disposed oblong stirrup 12 is secured to the under sides of the beams 1, is curved concentric with the king-bolt, and extends laterally at each side of the machine. The stirrup is constructed of angle-iron and is provided at its

longitudinally-opposite sides with registering perforations 13. An inverted-V-shaped pin, 50 having an upper terminal 14 and a lower terminal 15, is mounted removably in the upper and lower openings, and a loop or handle 15' is connected to the upper terminal mentioned. This pin may be withdrawn from the stirrup 55 by the attendant mounted on the platform 5, and have its terminals inserted into any of the pairs of openings 13 of the stirrup. The scraper-bar 11 is provided at its rear end with an opening 16, and the same loosely receives 60 the rear terminal of the pin just described. From this it will be obvious that the scraper-bar moving upon its pivot, the king-bolt 7 may have its rear end swung laterally at a desired angle to the machine, and may there 65 be secured by means of the inverted-V-shaped pin.

Vertical bolts 17 pass upwardly through the bar 11 and support above the bar an inverted-U-shaped hood 18, extending nearly 70 throughout the length of the bar 11. The hood, being U-shaped in cross-section and being spaced from the bar 11 by reason of its opposite flanges being thus held out of contact with said bar, combines with the bar to 75 form opposite longitudinal slots 19. The bar is provided at its front end at its opposite sides with keepers or openings 20, (best shown in Fig. 2,) and in the same take the depending hooks 21, formed at the front end of the 80 locking-latch 22. This locking-latch, which I have shown in detail in Fig. 5, comprises a pair of opposite parallel plates or flanges 23, and it is at the front ends of these plates that the hooks 21 are formed. Inverted-U-shaped 85 bails 24 are secured at their terminals to the plates 23, and the latter embraces the opposite longitudinal sides of the inverted-U-shaped hood 18. The plates or flanges 23 extend down over the longitudinal slots 19, and 90 the under edges of said plates are at intervals and opposite each other provided with notches 25.

In bearing-lugs formed upon the inverted-U-shaped hood 18, directly in rear of each of 95 the bails 24 of the locking-latch, bell-crank

levers 26 are pivoted, there being in this instance two bails and two levers. The lower branches or members of the levers are convexed to constitute cams 27, and above each 5 of said members there extends from the vertical portions of the levers a locking-lug 28. The upper ends of the bell-cranks are connected by a bar 29, pivoted, as at 30, to the said bell-crank. To the rear end of the hood 10 there is pivoted, as at 31, a simple lever 32, and the same is connected by a wire or rod 33 with the rear end of the connecting-rod 29. By this construction it will be seen that by a 15 rearward movement upon the part of the lever 32, which may be accomplished by the hand of the operator, the aforesaid bell-cranks may be swung to the rear, their cam-faces 27 rising under the bails 24, and thus elevating the locking-latch, so that the lower edges of 20 its side plates or flanges 23 are elevated above the flanges of the inverted-U-shaped hood 18, or, rather, the longitudinal slots 19, formed by the hood and bar 11. Of course such elevating of the latch will be permitted 25 by the withdrawal of the locking-lugs 28 from over the bails 24. By swinging the lever 32 to the front the movement is reversed, the locking-latch being lowered, and the lugs 28 swung over upon and lock the bails and 30 locking-latch in a lowered or depressed position.

34 designates the transversely - curved scraper-blade, to the rear side of which at its center brackets 35 are secured. A pin or bolt 36 is secured in the upper bracket, as best shown in Fig. 4. A V-shaped brace 37 has its front branch pivoted upon the bolt 36, its lower angular end reduced and pivoted, as at 38, to the lower bracket 35, and its rear 10 end bolted by one of the bolts 17 to the under side of the reach-bar. The pin or bolt 36 also passes through the rear bar 11, so that the bracket is rigid and the scraper-blade capable of swinging laterally upon the pivots 15 36 and 38. Vertically-opposite pairs of brackets 39 are also secured to the rear side of the scraper-blade near the ends thereof, and from each of these brackets extend rearwardly a metal strap 40, the forward ends of 20 50 which are pivoted by bolts 41 to the brackets and the rear ends of which are converged, meet, and are pivotally connected to themselves and to the ends of a horizontal connecting-bar 42 by means of pivoting-bolts 43. The rear pair of bolts 17 of the bar 11 are 25 55 connected by a rest-bar 44, and over this is mounted for sliding the just-described bar 42. 45 designates the curved beams or draft-arms of the scraper-blade, and the same pass 60 in rear of said blade, have their rear ends pivoted to the lower brackets 39, as shown, and are clipped by clips 46 to metal straps 47, mounted pivotally upon the upper bolts 41 of the brackets 39. The front-ends of the 65 beams 45 converge, are inwardly bent, and terminate in upturned stops or fingers, thus

making the ends of the beams L-shaped, as indicated at 48. These L-shaped ends or fingers engage with the slots 19, the horizontal portions of the ends riding in the slots, 70 and the fingers or bent ends of the beams riding against the inner faces of the flanges of the hood 18. By raising the locking-latch in the manner heretofore described—that is, through the medium of the lever 32—and 75 swinging the scraper to the right or left, thus changing the relative positions of the beams 45 and releasing the latch, the notches of the latter will take over and receive the front extremities of the beams, and thus lock the 80 beams against movement, so that the scraper after having been moved to any desired angle by suitable mechanism may be locked and retained against any undesired displacement. Various mechanisms may be employed 85 for operating the scraper, but I prefer the mechanism hereinafter described for this purpose.

In Figs. 1 and 7, 49 designates a pair of side cutters or wings, which are provided 90 with L-shaped metal straps 50, secured to their faces, said straps having adjusting-holes 51, by means of which they may be secured through the medium of bolts to the opposite ends of the scraper-blade. These 95 wings or side scrapers 49 are secured to the opposite ends of the blade or scraper when the same is set at a right angle to the line of draft of the machine, or substantially so, and said machine is employed for shoveling or 100 drawing dirt from one point to another. By the employment of these beams or side scrapers the capacity of the scraping-blade is increased, as the dirt cannot run off the sides or ends, as it would were such wings or blades 105 not present.

In standards 52, supported on the rear ends of the beams 1, there are journaled two transverse shafts 53, and the said shafts have mounted rigidly thereon near their extremities a pair of beveled pinions 54, and between the same a pair of hand-wheels 55. Upon the beams or sills 1, in front of the shafts 53, bearings 56 are located, and in the same a pair of opposite longitudinal shafts 57 110 are journaled. These shafts are each provided at their rear ends with a beveled gear 58, meshing with a pinion 54, and at their front ends with small beveled pinions 59. In arched standards 60, located in front of the pinions 59, short transverse shafts 61 are journaled, and each of these shafts is provided at its outer end with a crank or rock-arm 62. Within the standard and between the beams or sills 1 beveled gears 63 are 115 mounted on the shafts 61, and the same are engaged and driven by the beveled pinions 59 of the shafts 57.

The crank or rock arms 62 are provided at their ends with U-shaped yokes 64, said 120 yokes being provided at their rear sides with pins 65, loosely journaled in the crank or

rock arms, and pivoted in each yoke by trunnions 66 is a sleeve 67, provided at its outer side with loops or keepers 68. The loops or keepers of each sleeve receive the 5 upper end of a scraper-blade suspension rod or standard 69, the same being perforated at intervals for the reception of adjusting-bolts 69, (best shown in Fig. 2,) and passing through the keepers 68 of the sleeve 67.

10 Spring brake-shoes 70 are secured to each of the standards 3 and normally press against the peripheries of the hand-wheels 55. Below each brake-shoe there is pivoted to the platform 5, as at 71, a foot-lever 72, and a 15 connecting-rod 73 leads from the free end of the brake 70 to the foot-lever. By this it will be seen that the hand-wheels 55 are constantly locked against rotation and may be released at any moment for such rotation by means of 20 the foot of the operator exerting downward pressure upon the foot-levers.

In a cross-bar 74 there is journaled a vertical shaft 75, and the same is provided at its upper end with a hand-wheel 76, by which 25 the shaft may be rotated. A bar 77 is provided at its rear end with an eye 78, which loosely receives the shaft 75, and at its front end has loosely journaled thereon a grooved roller 79, mounted upon a transverse track 80, 30 located between the two inner sills or beams 1 of the frame. Between its ends the bar 77 is provided with an elongated eye 81, and in this is journaled the short transverse shaft 82 of a grooved pulley 83. A chain 84 has 35 one end connected to the shaft 75, and its front end passed over the pulley 83, below which it depends, and is connected by links 85 to the inverted-U-shaped hood 18, heretofore described.

40 Upon the front edge of the cross-bar 74 a vertical standard 86 is mounted, the upper end of said standard extending inwardly, and being perforated to receive a vertical detent or bolt 87, the lower end of which is, through 45 the medium of its coiled spring 88, that encircles the same, normally pressed into engagement with the indentations or teeth formed in the periphery of a ratchet-wheel 89, which is mounted fixedly upon the shaft 50 75. From the rear edge of the aforesaid cross-bar 74 rises a short standard 90, and the same has fulcrumed, as at 91, upon its upper end, a lever 92. This lever has its front end pivoted, as at 93, to the upper end of the bolt 87, 55 and its rear end is connected by a rod 94 to the lower front end of a foot-lever 95, fulcrumed, as at 96, upon the platform 5, as best shown in Figs. 1 and 2.

By operating the wheel 76 it will be seen 60 that the chain 84 may be wound upon the shaft 75. Previous to such operation, however, the two hand-wheels are rotated until, through the medium of their connections, the gears 63 and their shafts 61 are rotated sufficiently to bring the rock-arms 62 to their highest or most elevated position—namely,

vertical. Such movements of the rock-arms through the medium of the standards 69 elevates the scraper-blade and the mechanism employed for supporting it—that is, the bar 70 11 and its hood 18, the ends of the bar 11 moving up the vertical clevis or bail 10 and the terminal 15 of the inverted-V-shaped adjusting-pin. It is at this time that the slack thus formed in the chain is taken up by rotating 75 the shaft 75 and winding the chain thereon. When operating this shaft for the purpose of taking up the chain, the foot-lever 95 is depressed, so as to raise the bolt from engagement with the ratchet, and thus liberate 80 the shaft. When thus suspended, by operating the hand-wheels 55 in opposite directions the scraper may be swung from side to side upon its pivot—that is, in a vertical manner—so as to raise or lower either end 85 thereof. By manipulating the inverted-V-shaped pin the rear end of the bar 11 may be adjusted in any of the perforations 13 of the stirrup, and thus disposed at an angle to the line of draft and give to the scraper-blade a 90 proper angle. It will thus be seen that the raising and lowering of the end of the blade may be accomplished from the platform 5 and with great facility, requiring but very little power or exertion and simply the rotations 95 of the wheels 55 and 76.

Having described my invention, what I claim is—

1. In a road-scraper, the combination, with the framework comprising the opposite side 100 beams, opposite short shafts mounted on the beams and adapted for rotation, beveled gears mounted on the shafts, rock-arms extending from the ends of the shafts, rear transverse shafts, hand-wheels mounted thereon, beveled 105 gears mounted at the sides of the hand-wheels, intermediate longitudinal shafts, and gears on the ends of the same, engaging those gears of the front and rear short shafts, of a scraper-blade, means for locking the same, and connections between the blade and the rock-arms, substantially as specified.

2. In a road-scraper, the combination, with the framework comprising the opposite side 110 beams, opposite short shafts mounted on the beams and adapted for rotation, beveled gears mounted on the shafts, rock-arms extending from the ends of the shafts, rear transverse shafts, hand-wheels mounted thereon, beveled 115 gears mounted at the sides of the hand-wheels, intermediate longitudinal shafts, and gears on the ends of the same, engaging those gears of the front and rear short shafts, of a pivoted scraper-blade located under the framework and standards loosely connected to the blade 120 and at their upper ends to the rock-arms, substantially as specified.

3. In a road-scraper, the combination, with the framework comprising the opposite side 125 beams, opposite short shafts mounted on the beams and adapted for rotation, beveled gears mounted on the shafts, rock-arms extending 130

- from the ends of the shafts, rear transverse shafts, hand-wheels mounted thereon, beveled gears mounted at the sides of the hand-wheels, intermediate longitudinal shafts, and gears on 5 the ends of the same, engaging those gears of the front and rear short shafts, of a scraper-blade pivoted below the framework, opposite standards loosely connected at their lower ends to the extremities of the blade, the yokes pivoted to each of the rock-arms, the sleeves pivotally mounted in the yokes and provided with keepers receiving the upper ends of the standards, and means for securing the sleeves upon the standard, substantially as specified. 15
4. In a road-scaper, the combination, with the framework comprising the opposite side-beams, opposite short shafts mounted on the beams and adapted for rotation, beveled gears 20 mounted on the shafts, rock-arms extending from the ends of the shafts, rear transverse shafts, hand-wheels mounted thereon, beveled gears mounted at the sides of the hand-wheels, intermediate longitudinal shafts, and gears on 25 the ends of the same, engaging those gears of the front and rear short shafts, of the scraper-blade located under the framework, connections between the ends of the same and the rock-arms, a scraper-bar located above the 30 blade, pivotal connections between the bar and blade, and means for raising and lowering the bar, substantially as specified.
5. In a road-scaper, the combination, with the framework, the vertically-movable scraper-bar, and the scraper-blade pivotally connected to the bar, of the vertical winding-shaft, the wheel on the end of the same, means for laterally adjusting the rear end of the bar, a rod loosely connected with the winding-shaft, terminating at its front end in a bearing and in rear of the same in an eye, grooved pulleys mounted on the bearing and in the eye, a transverse track for the front pulley, and a chain connected with the winding-shaft and 45 passing over the pulley of the eye and having its lower end connected to the scraper-bar, substantially as specified.
6. In a road-scaper, the combination, with the framework having the platform at the 50 rear end of the same, the longitudinally-disposed scraper-bar, the blade pivoted to the bar, and means for oscillating the same, of a winding-shaft, a cross-bar having a bearing for supporting the same, a wheel at the upper end of the shaft, a ratchet-wheel mounted on the shaft, a standard at one side of the ratchet-wheel, a vertical spring-pressed bolt for engaging the wheel, mounted in the standard, a fulcrum-standard at the opposite side 55 of the shaft, a lever pivoted therein and connected at its front end to the bolt, a foot-lever mounted on the platform, a connecting-rod between the same and the free end of the lever, and a chain connected to the winding-shaft and to the scraper-bar, substantially as specified. 60
7. In a road-scaper, the combination, with the front and rear trucks and the connecting-framework, of the curved oblong stirrup secured to the under side of the framework in front of the rear truck and provided with upper and lower registering perforations, the scraper-bar pivoted to the front truck and having its rear end provided with openings and overlapping the said stirrup, and the inverted-V-shaped pin having the long and short terminals 15 and 14, respectively, adapted to pass through the perforations of the stirrup and scraper-bar, substantially as specified. 70
8. In a road-scaper, the combination, with the framework and the longitudinally-disposed scraper-bar, of the inverted-U-shaped bar 18, the opposite edges of which combine with the scraper-bar to form opposite longitudinal slots, the opposite latch-plates 23, having transverse keepers 24 for connecting the same, the pivoted scraper-blade located under the bar, beams pivotally connected to the blade and terminating at their front ends 80 in inwardly-disposed and upwardly-bent fingers mounted in the slots between the hood and bar, notches for engaging the fingers, formed at the lower edges of the opposite plates 23, and means for raising and lowering the said plates, so as to disengage the fingers, substantially as specified.
9. In a road-scaper, the combination, with the front and rear trucks and connecting-framework, of the scraper-bar having slots at opposite sides of its front end, bolts passed through the bar, an inverted-U-shaped hood mounted on the bolts and spaced upon the bar and combining therewith to form opposite slots, a scraper-blade pivoted to the underside of the bar, scraper-beams pivotally connected to the blade and having their ends inwardly and upwardly bent, as at 48, to engage the slots between the bar and hood, the opposite plates 23, terminating in depending fingers 90 21, engaging the slots at the front end of the bar, the transverse keepers 24, connecting the plates 23, the bell-cranks pivoted to the hood in rear of the keepers, said bell-cranks having their lower branches convexed to 95 form cams 27 and above the same provided with locking-lugs 28 for engaging the keepers, the connecting-rod 29, the lever 32, and the connecting-rod 33 between the lever and connecting-rod 29, substantially as specified. 100
10. In a road-scaper, the combination, with the scraper-bar and the scraper located below the same, of the opposite end brackets 39, the beams 45, loosely connected at their front ends to the scraper-bar and at their rear ends pivoted in the lower brackets and loosely clipped to the upper brackets, the upper and lower braces 40, pivoted in said brackets, the cross-bar 42, connecting the ends of said braces, the rest-bar 44, over which the scraper-bar passes, bolts connecting the cross-bar to the scraper-bar, the upper and lower cen- 105
11. In a road-scaper, the combination, with the scraper-bar and the scraper located below the same, of the opposite end brackets 39, the beams 45, loosely connected at their front ends to the scraper-bar and at their rear ends pivoted in the lower brackets and loosely clipped to the upper brackets, the upper and lower braces 40, pivoted in said brackets, the cross-bar 42, connecting the ends of said braces, the rest-bar 44, over which the scraper-bar passes, bolts connecting the cross-bar to the scraper-bar, the upper and lower cen- 110
12. In a road-scaper, the combination, with the scraper-bar and the scraper located below the same, of the opposite end brackets 39, the beams 45, loosely connected at their front ends to the scraper-bar and at their rear ends pivoted in the lower brackets and loosely clipped to the upper brackets, the upper and lower braces 40, pivoted in said brackets, the cross-bar 42, connecting the ends of said braces, the rest-bar 44, over which the scraper-bar passes, bolts connecting the cross-bar to the scraper-bar, the upper and lower cen- 115
13. In a road-scaper, the combination, with the scraper-bar and the scraper located below the same, of the opposite end brackets 39, the beams 45, loosely connected at their front ends to the scraper-bar and at their rear ends pivoted in the lower brackets and loosely clipped to the upper brackets, the upper and lower braces 40, pivoted in said brackets, the cross-bar 42, connecting the ends of said braces, the rest-bar 44, over which the scraper-bar passes, bolts connecting the cross-bar to the scraper-bar, the upper and lower cen- 120
14. In a road-scaper, the combination, with the scraper-bar and the scraper located below the same, of the opposite end brackets 39, the beams 45, loosely connected at their front ends to the scraper-bar and at their rear ends pivoted in the lower brackets and loosely clipped to the upper brackets, the upper and lower braces 40, pivoted in said brackets, the cross-bar 42, connecting the ends of said braces, the rest-bar 44, over which the scraper-bar passes, bolts connecting the cross-bar to the scraper-bar, the upper and lower cen- 125

trally-located brackets 35, and the V-shaped brace 37, having its lower ends swiveled in the lower bracket and its front branch pivotally connected to the scraper at its upper bracket 5 and its two branches rigidly bolted to the scraper-bar, substantially as specified.

In testimony that I claim the foregoing as

my own I have hereto affixed my signature in the presence of two witnesses.

JAMES M. HOLLAND.
